UNITED STATES PATENT OFFICE.

GEORGE C. BREIDERT, OF CHICAGO, ILLINOIS, ASSIGNOR TO AUTO UTILITIES MANUFACTURING COMPANY, OF CHICAGO, ILLINOIS, A CORPORATION OF ILLINOIS.

CAR-VENTILATOR.

1,113,302.

Specification of Letters Patent.

Patented Oct. 13, 1914.

Application filed February 19, 1914. Serial No. 819,817.

To all whom it may concern:

Be it known that I, GEORGE C. BREIDERT, a citizen of the United States, residing at Chicago, in the county of Cook and State of Illinois, have invented certain new and useful Improvements in Car-Ventilators, of which the following is a specification.

My invention relates to devices for ventilating railway cars or other vehicles or moving structures, of the type which operate on the principle of creating drafts across exhaust orifices by means of air ramming faces disposed at substantially right angles to the direction of travel of the car so that the movement of the car causes an impingement of air against the same, and arranged with respect to the exhaust orifices so that the impinging air will be directed unobstructedly across said orifices to produce a suction or vacuum in the device operating to withdraw foul air from the car.

The object of the invention is to provide certain improvements in a car ventilator of this type. These improvements consist first, of a novel contour for the air ramming faces whereby the impinging air is directed with certainty over the edges of the faces adjacent said exhaust orifices, and its waste, by escaping over the other edges of said faces prevented or at least minimized; second, in certain devices and arrangements for baffling or intercepting dust, cinders, rain, and the like, and preventing the same from entering the car through the exhaust orifices; third, in a construction of parts which obviates the possibility of back drafts into the car in whatever direction the wind may be blowing; and, finally, in certain other improved constructions, arrangements and devices relating to car ventilators to be hereinafter described and claimed.

While the invention preferably employs in combination, as shown in the drawings, the several improvements disclosed, it is realized that these features might be separately used to advantage in ventilators somewhat differently constructed from the preferred form shown, but of the same general type.

The invention is illustrated in certain preferred embodiments in the accompanying drawings, wherein—

Figure 1 is a fragmentary view, in perspective, of the top of a monitor deck car of ordinary construction, with a ventilator con-

structed in accordance with my invention attached to the deck sash so as to communicate with the car through one of the deck sash windows; Fig. 2 a view in perspective, on an enlarged scale, of the ventilator shown in Fig. 1; Fig. 3, a sectional view on line 3—3 of Fig. 2; Fig. 4, a sectional view on line 4—4 of Fig. 3; Fig. 5, a sectional view on line 5—5 of Fig. 2; Fig. 6, a detail sectional view taken on line 6—6 of Fig. 5 showing particularly the construction of the louvers and vertical baffling or deflecting strips; and Fig. 7, a fragmentary view in perspective, showing these constructions in fuller detail.

Like characters of reference designate like parts in the several figures of the drawings.

The ventilator of my invention has been shown and will be described in the position which it will assume when attached to the deck sash of the car. It should be understood that the device might be placed on the top of the car with the edges of the air ramming faces adjacent the exhaust orifices vertical instead of being horizontal, as they are when the device is attached to the deck sash. The relative terms "upper," "lower," "side," and "end" used in the description and claims herein, should be understood to refer to the respective parts of the device in its position attached to the deck sash. It is not intended, by the use of such terms, to limit the invention to this particular position of ventilator.

Referring to the drawings, 25 designates the deck of a monitor roof type of railway car and 26 the deck sash of the car.

The ventilator consists of a box-like hollow structure, preferably mounted on a hollow base or ring, provided with flanges for attachment to the deck sash of the car; the device being mounted over one of the deck sash window openings through which it is in communication with the interior of the car. The base consists preferably of side members 27 and top and bottom members 28, 29, which diverge in the direction away from the car. The bottom member 29 is formed with drainage outlets 30. By its oblique position this member provides a gutter to intercept water which may find its way into the base or ring. Such water is discharged through the drainage openings 30. The side and top and bottom members of the base are formed with flanges 31 by means of which

the ventilator may be secured to the deck sash 26. The opening from the base or ring into the body of the ventilator is narrowed by partitions 32, preferably formed continuous with the top and bottom members 28, 29, and further, by converging flanges 33 which extend into the body of the ventilator from the sides, top and bottom of the base, and serve to intercept foreign matter and prevent the same from entering the car through the ventilator. The body of the ventilator consists of a pair of air ramming faces 34, and an imperforate end 35. These parts may be made of one strip of metal suitably bent and secured to the base. The top and bottom of the body portion of the ventilator are open, constituting air orifices 36 between the oppositely disposed air ramming faces 34. The latter are preferably bent on the diagonal lines shown so that the center portion of the face, in each case, constitutes a diamond shaped wedge 37 which projects out farthest at its center line 38, and from that line is inclined inwardly on opposite sides toward the exhaust orifices. This gives the edges 39 of the air ramming faces adjacent the exhaust orifices a central depression or bend, and also causes each triangular corner portion 40 of the face to slope inwardly from the corner of the face toward the central wedge portion 37. The purpose of this configuration is to direct the air impinging against the face toward the edges 39, and thence over the exhaust orifices, preventing or minimizing the escape of air over the edge of the face adjacent the closed end 35 of the ventilator. The air ramming faces, as a whole, are at right angles to the line of travel of the car. It has been found, however, by actual experiment, that by bending the faces on the diagonal lines, as above described, a much greater efficiency is attained than if the faces were perfectly flat. The central wedging portion 45 divides the air and directs it toward the upper and lower exhaust orifices. The slight inward inclination of the corner portions of the face prevents the air from escaping in any considerable volume over the outer end of the ventilator. The air ramming face is not specifically claimed herein, being claimed in my co-pending application Serial No. 767,088, filed May 12, 1913.

The exhaust orifices are preferably provided each with a set of parallel louvers 41 which extend across the openings from one air ramming face to the other. These louvers are connected by sets of vertical baffling or deflecting strips 42, one set at each of the devices adjacent the air ramming faces but preferably spaced a short distance from the same. The louvers are preferably formed with lips 43 outwardly inclined with respect to the car.

65 The constructions just described have

proven to be eminently well calculated to baffle and intercept dust, cinders, rain and the like, and prevent the same from entering the car. At the same time, they do not in any way hinder the exhausting operation of the ventilator or give rise to choking or back drafts. The arrangement is such as to be effective, in both particulars noted, regardless of the direction in which the wind may be blowing. The vertical deflecting strips are particularly well calculated to prevent cinders from entering the car through the ventilator. The ventilator, it will be seen, is open at the top. There is nothing to prevent cinders from the locomotive dropping through the spaces between louvers 41. If the vertical strips were omitted, the wind or the motion of the train might cause the cinders to impinge upon the inside of the rear one of the air ramming faces and be therefrom deflected into the car through the deck sash opening. The vertical deflecting strips adjacent this face serve to break the velocity of the cinders and moreover, by standing between the inside of such face and the opening into the car, prevent any impinging cinders from reaching the opening. The cinders striking against the rear set of deflecting strips, are checked in their movement and precipitated out of the device through the lower set of openings. The horizontally extending louvers 41 similarly intercept and break the velocity of cinders which may blow into the upper exhaust orifice in directions transverse or oblique to the louvers. Such cinders fall out of the lower exhaust orifice. The constant exhaust through the apparatus, together with the position of the converging flanges 33 surrounding the opening between the body of the ventilator and the base, further serve to prevent foreign matter in suspension in the air from entering the car through the ventilator. When the ventilator is arranged in vertical position, the converging flanges 33 serve the purpose of providing a gutter for collecting and discharging water which may be driven into the ventilator through the open sides thereof.

The ventilator above described is intended particularly for steam railway service, although it might be used upon street cars. In order to give the device great strength and rigidity, having in view particularly this service on steam roads, the louvers and deflecting strips are made to serve not only the function above described, but are also so constructed and disposed that they add materially to the strength of the entire structure. The louvers 41 are formed at each end with a foot 44, which stands at right angles to the louver and is seated in beads 45 formed on a strip 46 which is united to the air ramming face by rivets 47. The feet of the inner louvers are preferably formed

with offsets 48 (Figs. 5, 6 and 7) against which the adjacent louvers bear. The parts may be united with solder where this is deemed expedient. The vertical deflecting strips 42 are formed on their edges with stiffening beads 49 and their extremities 50 are fitted in the beads 51 formed on the edges of the louvers 41.

While I have described my invention in certain preferred embodiments, modifications might be made without departure from the principles of the invention. Therefore, I do not wish to be understood as limiting the invention to the exact constructions, devices and arrangements shown, except so far as said constructions, devices and arrangements are specifically made limitations in certain of the claims herein.

I claim:

1. A car ventilator comprising a hollow structure, having an open side adapted to communicate with the interior of the car, oppositely disposed air ramming faces, exhaust orifices between said faces, and a set of deflecting strips extending through said hollow structure adjacent to each air ramming face disposed edgewise to said faces and extending from one exhaust orifice to the other.

2. A car ventilator comprising a hollow structure, having an open side adapted to communicate with the interior of the car, oppositely disposed air ramming faces, exhaust orifices between said faces, and a set of deflecting strips extending through said hollow structure adjacent to each air ramming face disposed edgewise to said faces but spaced therefrom and extending from one exhaust orifice to the other.

3. A car ventilator comprising a hollow structure, having an open side adapted to communicate with the interior of the car, oppositely disposed air ramming faces, exhaust orifices between said faces, parallel louvers extending across said exhaust orifices, and deflecting strips within said hollow structure adjacent to said air ramming faces respectively and extending edgewise across the same.

4. A car ventilator comprising a hollow structure, having an open side adapted to communicate with the interior of the car, oppositely disposed air ramming faces, exhaust orifices between said faces, a set of parallel louvers extending across each exhaust orifice from one air ramming face to the other, and deflecting strips within said hollow structure adjacent each air ramming face and extending from one set of louvers to the other.

5. A car ventilator comprising a hollow structure, having an open side adapted to communicate with the interior of the car, an air ramming face, an exhaust orifice, and parallel deflecting strips within said hollow

structure adjacent to and extending edge-wise across said air ramming face.

6. A car ventilator comprising a hollow structure, having an open side adapted to communicate with the interior of the car, an air ramming face, an exhaust orifice, parallel deflecting strips within said hollow structure adjacent said air ramming face, and parallel louvers extending across said exhaust orifice.

7. A car ventilator comprising a hollow structure, having an open side adapted to communicate with the interior of the car, an air ramming face, an exhaust orifice, parallel deflecting strips within said hollow structure adjacent said air ramming face, and parallel louvers extending across said exhaust orifice at right angles to said air ramming face.

8. A car ventilator comprising a hollow box-like structure, formed with oppositely disposed air ramming faces and with exhaust orifices between said faces, a hollow base on which said box-like structure is mounted, formed with converging flanges which project into said box-like structure, a set of parallel louvers extending across each exhaust orifice from one air ramming face to the other, and a set of parallel deflecting strips within said hollow box-like structure adjacent to and extending edge-wise across each of said air ramming faces.

9. A car ventilator comprising a hollow box-like structure, formed with oppositely disposed air ramming faces and with exhaust orifices between said faces, a hollow base on which said box-like structure is mounted, formed with converging flanges which project into said box-like structure, a set of parallel louvers extending across each exhaust orifice from one air ramming face to the other, and a set of parallel deflecting strips within said hollow box-like structure adjacent each of said air ramming faces, one side of said base being inclined downwardly and outwardly so as to provide a gutter and being formed with drainage openings.

10. The combination with a ventilator formed with an exhaust orifice, of parallel louvers extending across said orifice formed with angularly disposed feet at opposite ends, and attaching strips secured to said ventilator on opposite sides of said exhaust orifice having marginal beads into which the angular feet of said louvers are fitted so as to be held in place thereby.

11. The combination with a ventilator formed with an exhaust orifice, of parallel louvers extending across said orifice formed with angularly disposed feet at opposite ends, and attaching strips secured to said ventilator on opposite sides of said exhaust orifice having marginal beads into which the angular feet of said louvers are fitted so as to be held in place thereby, certain of said

4 feet being formed with off-set portions against which adjacent louvers bear.

12. The combination with a ventilator formed with an exhaust orifice, of parallel louvers extending across said orifice formed with angularly disposed feet at opposite ends, attaching strips to which said feet are attached, said louvers being formed with beads and deflecting strips arranged at 10 right angles to said louvers, the extremities of which are fitted into said beads.

13. The combination with a ventilator formed with an exhaust orifice, of parallel louvers extending across said orifice formed with angularly disposed feet at opposite ends, attachment strips at opposite sides of said ventilator formed with beads at their edges into which the angular feet of the louvers are fitted so as to be held in place 20 thereby, said louvers being formed with beads on their outer edges and deflecting strips arranged at right angles to the louvers extending across the structure from one set of louvers to the other with their extremities 25 fitted into the beads with which said louvers are formed.

14. A car ventilator comprising a box-like structure having an open side communicating with the interior of the car, a pair of 30 relatively oppositely disposed imperforate air ramming faces at right angles to the direction of travel of the car, an imperforate outer end wall, relatively oppositely ar-

ranged exhaust openings between said air ramming faces, parallel louvers in said exhaust openings extending from one air ramming face to the other and formed at their extremities with angularly disposed feet, and attaching strips secured to the inner surfaces of said air ramming faces having 40 marginal beads into which the angular feet on said louvers are fitted so as to be held in place thereby.

15. A car ventilator comprising a box-like structure having an open side communicating with the interior of the car, a pair of relatively oppositely disposed imperforate air ramming faces at right angles to the direction of travel of the car, an imperforate outer end wall, relatively oppositely arranged exhaust openings between said air ramming faces, parallel louvers in said exhaust openings extending from one air ramming face to the other and formed at their extremities with angularly disposed feet, 50 and attaching strips secured to the inner surfaces of said air ramming faces having marginal beads into which the angular feet on said louvers are fitted so as to be held in place thereby, said feet being formed at their edges with spacing off-sets against which the adjacent louvers bear.

GEORGE C. BREIDERT.
